UNITED STATES PATENT OFFICE

JOSEPH PETER EASTMAN, OF MANITOWOC, WISCONSIN, ASSIGNOR TO EASTMAN MFG.
CO., OF MANITOWOC, WISCONSIN, A CORPORATION

ATTACHMENT PLUG

Application filed November 19, 1925. Serial No. 70,024.

This invention relates to an attachment plug, and is particularly directed to means for relieving the strain of the cord leading to the plug.

5 Objects of this invention are to provide a device which is so constructed that it may carry the usual thimbles for receiving the prongs of an electrical device, such for instance as an iron, toaster, or other apparatus, and which is so constructed that the attached ends of the cord are held permanently in place without placing any strain thereon even if the main cord should be inadvertently pulled.

10 Further objects are to provide a novel form of device for supporting the cord and preventing its being broken by a sharp bend, and to so organize this device that it is rigidly secured within the insulating member 20 or head enclosing the thimbles.

An embodiment of the invention is shown in the accompanying drawing, in which:—

Figure 1 is a view of the device with parts broken away.

25 Figure 2 is an enlarged view partly in section with parts broken away.

Figure 3 is a section on the line 3—3 of Figure 2.

Referring to the drawing, it will be seen 30 that the device comprises a head 1 of insulating material formed of two members slit along a longitudinal plane.

These members are provided with channels 2 which receive the thimbles 3 of the device. These thimbles are provided with screws 4 at their inner ends which receive the terminals of the wires 5 carried in the cables 6. It is to be noted that the head or enclosing member 1 is provided with a tubular neck 7 which is equipped with an annular recess 8 having a hexagonal periphery. Within this recess, the hexagonal flange 9 of a nipple or body piece 10 is positioned, such nipple projecting outwardly therefrom 45 and having a threaded extension, and a nut or union-like member or shell 11 is also provided with an internally threaded portion so that the threads may be screwed together, as indicated at 12 in Figure 2. This nut is provided with an outwardly elongated hub 13

provided with a plurality of grooves 14 there-in forming a helix to receive and retain the helical supporting coil 15 (see Figure 1). The outer end of such coil carries an insulating bushing 16. This coil, it will be seen, is rigidly held upon the hub of the nut, and the nut is in turn carried by the rigidly held nipple 10.

The juxtaposed portions of the nut and of the nipple are provided with curved faces 17 and 18 which receive between them the clamping sleeve 19. This clamping sleeve is provided with a spherical external surface and with a plurality of slots 20 to permit its contraction. The internal surface of the clamping sleeve 19 is provided with small serrations 21 which grip the cable 6 when the nut is screwed into place.

It will be seen that the cable is gripped by the gripping sleeve 19 and prevented from being withdrawn from the apparatus, thus relieving the attached ends of the cable from strain.

Further, it will be particularly noted that the nipple 10 is rigidly carried within the recessed portion of the neck 7 of the head of the device. This nipple also rigidly carries the nut 11 which in turn supports the helical coil 15. Thus inadvertent shifting of the supporting portions is prevented and further rotary motion is prevented, as the hexagonal flange 9 fits accurately the hexagonal recess 8 of the neck.

It will be seen that a very serviceable and practical type of electrical fixture has been provided which has novel characteristics, and which fulfills a long felt want, affording the utmost security of attachment of the cable and adequate support therefore adjacent the head of the device.

Although the invention has been described in considerable detail, such description is intended as illustrative rather than limiting as the invention may be variously embodied and as the scope of such invention is to be determined as claimed.

I claim:

An attachment plug of the character described including a body nipple having an annular curved inner face at one end there-

of, a hexagonal flange around the exterior of the body at the other end, screw threads on the exterior of the body at the end provided with the annular curved face, an elongated hub having an enlarged portion with an inner curved face and an inner threaded portion adjacent the curved face adapted to cooperate with the threads on the body nipple, a clamping sleeve having a spherical external surface adapted to cooperate with the curved face on the body nipple and the hub, said clamping sleeve having a plurality of slots extending inwardly from the ends thereof whereby when the elongated hub is threaded onto the body nipple, the clamping sleeve will be contracted and a plurality of serrations on the inner face of the clamping sleeve adapted to be moved into engagement with a yieldable object arranged in the sleeve.

20 In testimony that I claim the foregoing I have hereunto set my hand at Manitowoc, in the county of Manitowoc and State of Wisconsin.

JOSEPH PETER EASTMAN.
